(57) **CLAIM**

The ornamental design for a tissue dispensing plush bear, as shown and described.

DESCRIPTION

FIG. 1 is a front elevation view of a tissue dispensing plush bear showing our new design;

FIG. 2 is a rear elevation view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevation view thereof, showing a tissue box compartment contained in the bear, in an open position.

The broken lines shown in the drawing are for illustrative purposes only and form no part of the claimed design.

The nose of the bear shown in the drawing is lined for the color red.
